UNITED STATES PATENT OFFICE.

BOY A. HATFIELD, OF NORRISTOWN, PENNSYLVANIA, ASSIGNOR TO HELEN S. HATFIELD, OF NORRISTOWN, PENNSYLVANIA.

CONVEYER.

Application filed July 26, 1926. Serial No. 124,964.

My invention relates to conveyers, and particularly to a conveyer constructed for conducting materials in an inclined direction.

5 One advantage of my device is that it will convey material up grade, the degree of grade varying with the size and kind of material.

Another advantage of my device is that 10 the direction of travel may be reversed, for example, coal may be conveyed from the mine to the cars and other materials may be conveyed from the cars to the mine, by a simple adjustment which causes the conveyer to reverse its direction of travel.

Another important feature of my device resides in means for supporting and operating a trough or other material supporting surface to effect travel of material along the 20 same.

A special feature of my device resides in the slotted fly-wheel which imparts motion to a pitman rod which in turn imparts a curvilinear motion to the conveyer trough.

25 This slot in the fly-wheel is important in that when the conveyer trough is abruptly halted in its line of travel by a bumper (I have found in practice that it is not advantageous to have a resilient bumper) the shock of the impact is not transmitted to 30 the driving means; the slot at the moment of impact being at such an angle that the pitman pivot block slides freely therein.

The fly-wheel has a slot in which a pivot 35 is slidably mounted. The pivot block is connected to a trough by means of a pitman rod. When the fly-wheel is revolved it moves the pivot block, which moves the pitman rod, which in turn elevates the trough. 40 When the angle of the slot in the fly-wheel has reached a predetermined angularity with the horizontal, the pivot block slides along the slot, actuated by the weight of the trough and its contents. The trough actuated by gravity, descends until abruptly checked by impact with the bumper blocks 45 mounted in the main frame. The successive elevating and sliding of the pivot block occurs twice per revolution of the fly-wheel.

50 Referring to the drawings:—

Fig. 1 is a side elevation of a conveyer constructed in accordance with my invention partly broken away to show more clearly the slotted fly-wheel.

Fig. 2 is a cross-section on the line 2—2 of Fig. 1.

Figs. 3, 4 and 5 together with Fig. 1 denote four successive positions of the pivot block, the bumper remaining in a given fixed position.

Figs. 6, 7, 8 and 9 denote four successive positions of the pivot block, the bumper remaining in a second given fixed position.

Referring more fully to the drawings, 1 indicates the main frame which I have shown 65 constructed of angle irons and steel straps, 2 denotes a material-supporting surface which I have shown in the form of a trough swung from links 3 which are in turn swung from the main frame 1.

The main frame 1 is provided with bumper blocks 4 adapted to be connected thereto by bolts 4^a having wing nuts 5. These blocks 4 are adapted to be fastened to the main frame 1, through the bolt holes 6 in 75 one position of adjustment and by the use of the bolt holes 6^a in another position of adjustment. The adjustment of the bumper blocks fore and aft together with other adjustments, to be set forth hereafter, reverse 80 the travel of material along the trough. The material-supporting surface 2 is provided with lugs 7 adapted to engage the said bumper blocks 4.

A fly-wheel 8, mounted adjacent to the 85 main frame 1 and suitably driven by any desired power, is provided with a slot 9. In this slot is slidably arranged pivot block 10 to which is pivoted a pitman rod 11.

The pitman rod is provided with a bolt 12 90 adapted to pivot in either of the grooves 13 or 13^a which grooves are cut in a bracket 13^b rigidly attached to the trough 2. The adjustment of the pitman rod together with the adjustment of the bumper blocks 4, reverses 95 the direction of travel of the material being conveyed. It being noted that when the blocks 4 are moved aft the pitman rod is also moved aft and when the bumper blocks 4 are moved forward the pitman is adjusted forward.

As shown in Figs. 1, 3, 4 and 5 my device is adapted to convey material toward the left and as shown in Figs. 6, 7, 8 and 9 my device is adapted to convey material toward 100 the right.

The materials are conveyed along the trough 2 by the descent of the trough, actu-

ated by gravity when the fall of the trough is abruptly arrested by the impact of lugs 7 against bumpers 4.

It will be noted that the weight of the trough together with the weight of the material therein, causes the trough, actuated by gravity, to drop with such force that in cases where the main frame is placed upon a hill-side, the links 3 will swing past the vertical position and ascend on an upward swing, until abruptly checked by the impact of the trough lugs 7 against the bumper blocks 4.

The inertia acquired by the material in the downward swing of the trough causes the material to continue along the trough after the trough has been abruptly stopped by the bumper blocks 4.

In Fig. 1 the fly-wheel has been rotated to a point where the pivot block 10 has no support and is ready to slide. The trough is shown in an elevated position exerting pressure upon the pitman rod 11 and the pivot block 10. This pressure on the pivot block 10 causes it to slide rapidly to the bottom of slot 9.

Fig. 3 shows the same position of the fly-wheel but the pivot block 10 is shown as having slid to the bottom of the slot 9, and the trough, actuated by gravity has been impelled against bumper blocks 4.

In Fig. 4 the fly-wheel has moved, but not far enough to change the position of the trough which is still in the same position as shown in Fig. 3.

In Fig. 5 the fly-wheel has moved far enough to push the pitman rod which in turn has pushed, and thus elevated the trough. It will be noted that in this drawing the pitman rod is at such an elevated angle that it is impossible for the pivot block 10 to drop, it being held in the slot 9 by the combined weight of the trough and its contents.

In the Figs. 6, 7, 8 and 9 the pitman rod 11 has been adjusted in the groove 13^a and the bumper blocks 4 have been adjusted to the holes 6^a.

This new adjustment reverses the direction of travel of the material being transported. In this adjustment the action of the pitman rod is reversed from that described in Figs. 1, 3, 4 and 5.

In Fig. 6 the fly-wheel has been rotated to a point where the pivot block 10 has no support and it is ready to slide.

Fig. 7 shows the same position of the fly-wheel but the pivot block 10 has slid to the top of the slot 9 and the trough, actuated by gravity has been impelled against bumper blocks 4.

In Fig. 8 the fly-wheel has moved, but not far enough to change the position of the trough which is still in the same position as shown in Fig. 7.

In Fig. 9 the fly-wheel has moved far

enough to pull the pitman which in turn has pulled and thus elevated the trough.

It will be seen from the foregoing that to move the material in one direction the trough is pushed and released, while moving the material in a reverse direction the trough is pulled and released.

It is also apparent that the trough falls by gravity twice per each revolution of the fly-wheel conveying the material along the trough at a rapid rate.

To illustrate the operation of my device, the trough 2, may be compared with a shovel. Now for example, if wet clay is placed upon a shovel the operator, using a throwing motion, must hold his shovel in the advanced throw position until the wet clay loosens its hold upon the surface of the shovel and slides in the direction of the throw. Now on the other hand when dry clay is placed upon a shovel the operator uses the same throwing motion but it is not necessary for him to hold his shovel in the advanced throw position as the material slides off easily. It is therefore seen that the operator can shovel dry material much faster than he can shovel wet material. The fly-wheel of my machine is adapted to operate at different speeds so that my conveying trough will handle wet or dry material as desired.

From the above it will be noted that when wet material is being transported it is necessary to allow the trough to remain in the advanced throw position for a greater length of time than when dry material is being transported.

The length of time the trough remains in the advanced throw position in my device is governed by the speed at which my flywheel is revolved.

As to the links 3 these are placed in pairs at desired intervals to support the trough to the main frame.

Having thus described my invention what I wish to claim and secure by Letters-Pat-ent is:

1. In a material conveyer, the combination of a supporting frame; a plurality of links pivotally pendant from said frame; a conveying trough pivotally connected to said links and provided with lugs; bumpers adjustably attached to said frame adapted for engagement with said lugs; a driving mechanism having a slotted fly-wheel; and a pitman rod adapted in one position of adjustment relative to said trough, to be pulled by said fly wheel and released from the action of said fly-wheel, and, in a second position of adjustment relative to said trough to be pushed by said fly-wheel and released from the action of said fly-wheel, once in every half revolution of said fly-wheel.

2. In a material conveyer, the combination of a supporting frame; a plurality of links pivotally pendant from said frame; a con-

veying trough pivotally connected to said links and provided with lugs; bumpers adjustably attached to said frame adapted for engagement with said lugs; a pitman rod adjustably connected to said trough; a driving mechanism having a slotted fly-wheel adapted to operate said pitman rod; and means for adjusting the positions of said pitman rod and said bumpers, fore and aft of said frame and said trough respectively, to determine the direction of travel imparted by said conveyer trough to material being transported therein.

3. In a conveying mechanism the combination of a supporting frame; a plurality of links pivotally pendant from said frame; a conveying trough having lugs, pivotally con-

nected to said links; bumpers adjustably attached to said frame adapted for engagement with said lugs; an independently mounted driving mechanism; means for adjusting said trough relative to said driving mechanism so that in one position of adjustment the trough is pulled and released and in another position of adjustment the trough is pushed and released whereby the material being conveyed will travel in one direction in one position of adjustment and in a reverse direction in the second position of adjustment.

In testimony that I claim the foregoing as my own, I affix my signature.

ROY A. HATFIELD.
